(57) **CLAIM**

What is claimed is the ornamental design for hooks on a hip bag, as shown and described.

DESCRIPTION

FIG. 1 is a perspective of my new design for hooks on a hip bag, according to a first Embodiment;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing a hip bag are for the purposes of illustrating environment and form no part of the claimed design.
